5

6

FIGURE 1 is a front perspective view of a tool grinder showing my design, an upper movable portion being at its right extreme position.

FIGURE 2 is a rear perspective view thereof.

FIGURE 3 is identical to FIGURE 1 showing the upper movable portion at its left extreme position.

FIGURE 4 is a front perspective view thereof, the movable portion being centered in this and in succeeding views.

FIGURE 5 is a side perspective view thereof.

FIGURE 6 is a top perspective view thereof.

FIGURE 7 is a rear perspective view thereof.

I claim:

The ornamental design of a tool grinder, or similar article, substantially as shown and described.
